UNITED STATES PATENT OFFICE

90,849

DESIGN FOR A TABLE

Christian R. Kayser, Los Angeles, Calif.

Application July 31, 1933. Serial No. 48,897

Term of patent 3½ years

To all whom it may concern:

Be it known that I, CHRISTIAN R. KAYSER, a citizen of the United States, residing at Los Angeles, in the county of Los Angeles and State of California, have invented a new, original, and ornamental Design for a Table, of which the following is a specification, reference being had to the accompanying drawing, forming a part thereof.

The figure is a perspective view of the table, showing my new design.

I claim:

The ornamental design for a table, as shown.
C. R. KAYSER.
